MEANS FOR PROTECTING ARTICLES OF FURNITURE AND THE LIKE

Filed Nov. 12, 1929

FIG. I.

Fig. 2.

Fig. 3.

A cross-sectional view of a cylindrical component. The left side shows a vertical bore with a ribbed wall. The right side shows a ribbed outer surface. Labels include: 19 (top left), 20 (top right), 15 (left side of bore), C (center of bore), and B (bottom left).

FIG. 4.

William T. Horner

884 Mr. Hodges Attorney

UNITED STATES PATENT OFFICE

WILLIAM T. HORMES, OF BALTIMORE, MARYLAND

MEANS FOR PROTECTING ARTICLES OF FURNITURE AND THE LIKE

Application filed November 12, 1929. Serial No. 406,639.

This invention is a device primarily designed as a protection for those surfaces of various articles of manufacture, which are normally so exposed that they are liable to be marred or injured by contact therewith, of harder objects which may be moved about in their vicinity.

In mercantile establishments, for instance, the legs of tables, counters, and other similar furniture are often seriously marred by being struck by passing hand trucks. Likewise shelving, and particularly the projecting portions of pilasters, are frequently scratched and otherwise defaced during the handling 10 of merchandise, and by careless manipulation of mops, scrubbing machines, floor polishing machines and the like, operated in their vicinity. The same is true of various articles of household furniture, which are frequently 15 damaged by contact with moving vacuum cleaners, floor polishing machines, etc.

One of the objects of the invention is to provide an armor-like protection, which may be arranged to cover those surfaces which 20 would be normally exposed to damage of the character described. A further object is to provide an armor means of the character mentioned, which may be readily applied to any surface requiring the desired protection, and which will be of a character to improve and greatly enhance the appearance of the article to which it is applied.

The invention will be hereinafter fully set forth and particularly pointed out in the 35 claims.

In the accompanying drawings:—

Figure 1 is a side elevation of a portion of a table with the invention applied thereto. Figure 2 is a cross sectional view on the line 40 2—2, Figure 1. Figure 3 is a cross sectional view on the line 3—3, Figure 1. Figure 4 is a detail view of one of the protector rods.

It is to be understood that although the invention is herein illustrated and described 45 as applied to a table, it is not limited to this

use, the selection of the table being solely for the purpose of illustration. In other words, the invention is applicable to all kinds of furniture, both store and household, to shelving, pilasters and panels, and to any other articles not here listed, to which the device covered by the appended claims may be applied.

Referring to the drawings, 10 designates a table which is provided with the usual legs, 50 one of said legs being indicated at 11. The details of the table construction are unimportant because they form no part of the invention.

Suitably secured to the leg 11 are two metal 55 retaining members A and B, respectively, which in practice are normally mounted in spaced relation. Said members may be retained in position in any desired manner. As shown in the drawings for purposes of illustration, each retaining member is provided at its ends with wings 12, angularly disposed with respect to the body of the member, and so shaped that they may enter kerfs or grooves 13 formed in the surface of the 60 article to be protected.

Each retaining member is provided with a longitudinally extended reduced portion C 65 near one edge, so as to provide a seat or abutment shoulder 14, and a retaining flange 15. In practice, the inner face of each retaining member bears against the plane surface 16 70 which is to be protected, so that a recess 17 is provided between said surface and the reduced portion C.

The surfaces 18 are protected by means of a plurality of metal rods 19, preferably of circular cross section and arranged in parallel abutted relation, their ends being anchored in any suitable manner. As shown 75 in the drawings there is a set of said rods for each exposed face of leg 11, and in practice it is preferred to provide both ends of each rod with cut-away portions 20, so that said ends may be projected into the recesses 80 85 90

17. By this arrangement the flattened surfaces of the cut-away portions 20 engage the inner surfaces of the flanges 14, so that they are normally held against rotation. The rods 19 are of sufficient diameter to provide an armor of substantial thickness over the area to be protected.

In the specific table illustrated, the top X, body Y, and legs Z are made separately, 10 the intermediate or body element Y being provided with grooves 13 to receive angular wings 12 on the members A and B. By means of this arrangement the bottom member B may be first positioned by engaging the 15 wings 12 with the grooves 13 of the element Y, and said element is then placed in position in engagement with the leg 11. The rods 19 at one end are engaged with the member B and then the member A is positioned so as 20 to engage the other extremities of said rods, after which the top X is placed in position, thereby holding the retaining members in place.

The rods 19 are constructed of any desired 25 metal of the required hardness, but experience has shown that by the selection of a metal which will produce a contrasting color with respect to the adjacent exposed surfaces of the article to which the protector is applied, a parallel arrangement of the rods in 30 itself not only provides a very ornamental surface, but the contrasting colors greatly enhance the appearance of the article after the device has been applied thereto. For example, assuming that the exposed surfaces of 35 the portion Y, Figure 1, are constructed of a material having an inherent color, such as rosewood or mahogany, for instance, by constructing the rods of a metal having a contrasting color, the protection of the article 40 is not only secured because the rods are of such a diameter that they extend beyond the plane of said surfaces, but the effect due to the contrasting colors adds greatly to the 45 appearance of the article to which the protector is applied.

Having thus explained the nature of the invention and described an operative manner 50 of constructing and using the same, although without attempting to set forth all of the forms in which it may be made, or all of the forms of its use, what is claimed is:—

1. A protection device of the character described comprising two spaced apart retaining members, means for securing said members to an article adjacent to a surface to be protected, and a plurality of parallel metal rods bearing against said surface and having their ends anchored within said retaining members.

2. A protection device of the character described comprising two spaced apart retaining members, each having a reduced portion forming a side flange and an abutment shoulder, means for securing said members

to an article adjacent to the surface to be protected, and a plurality of parallel metal rods bearing against said surface and so positioned that their ends bear upon said seats and are overlapped by said flanges. 70

3. A protection device of the character described comprising two spaced apart retaining members, each having a reduced portion forming an abutment shoulder and a side flange, means by which said retaining members may be secured to an article adjacent to the surface to be protected, and parallel rods covering said surface, said rods having cut-away portions at their ends, so as to provide shouldered projections complementary to said 75 abutment shoulder. 80

4. A protection device of the character described comprising two spaced apart retaining members, means for securing said members to an article adjacent to the surface to be protected, and a plurality of parallel metal rods of circular cross section arranged in longitudinal abutting relation against the said surface, said rods having shoulders at their extremities, means being provided to 85 engage said shoulders so as to prevent rotation of said rods. 90

5. The combination with an article to be protected provided with a plane surface, and also with parallel grooves in spaced apart 95 relation adjacent said surface, of two spaced apart retaining members each having wings extended into said grooves, so as to hold the members in position, and a plurality of parallel rods bearing against said surface, and 100 having their ends engaged by said retaining members, so as to retain them in position, said rods being arranged in abutted parallel relation.

6. The combination with an article to be 105 protected provided with a plane surface, of two spaced apart retaining members each provided with a reduced portion forming a flange, and an abutment shoulder, means for securing said members to said article adjacent to said surface, with the inner surfaces 110 of the members in contact therewith, and a plurality of metal rods bearing against said surface and disposed in parallel relation, the extremities of said rods having portions complementary to said shoulders and flanges, so 115 that while the rods are engaged with said retaining members they are held against rotation.

7. The combination with a table leg of 120 polygonal cross section providing a plurality of plane surfaces, of a plurality of sets of parallel metal armor rods extending longitudinally over the respective surfaces, so that said rods will receive the impact resulting 125 from blows imparted by articles moving in the vicinity of said leg, and means retaining said rods in position.

8. The combination with a table leg of 130 polygonal cross section providing a plurality

of plane surfaces, of a plurality of sets of parallel metal armor rods extending longitudinally over the respective surfaces, so that said rods will receive the impact resulting from blows imparted by articles moving in
5 the vicinity of said leg, and a pair of spaced apart retaining members engaged with said leg so as to hold said rods in place, said retaining members being of an angular form complementary to the cross section of said leg.

10 In testimony whereof I have hereunto set my hand.

WILLIAM T. HORMES.
